(57) **CLAIM**

The ornamental design for a shaping and boring tool with adjustable depth gauge, as shown and described.

DESCRIPTION

FIG. 1 is a left side view of the shaping and boring tool with adjustable depth gauge, showing the depth gauge in a low position;

FIG. 2 is a rear view of the shaping and boring tool with adjustable depth gauge of FIG. 1;

FIG. 3 is a front view of the shaping and boring tool with adjustable depth gauge of FIG. 1;

FIG. 4 is a rear isometric view of the shaping and boring tool with adjustable depth gauge of FIG. 1;

FIG. 5 is a front isometric view of the shaping and boring tool with adjustable depth gauge of FIG. 1;

FIG. 6 is an isometric view from above of the shaping and boring tool with adjustable depth gauge of FIG. 1; and,

FIG. 7 is an isometric view of the shaping and boring tool with adjustable depth gauge removed.

The shaping and boring tool with adjustable depth gauge is for the freehand shaping and boring of wood.
